UNITED STATES PATENT OFFICE.

RAYMOND L. MEYERS, OF MIAMI, FLORIDA.

STORMPROOF AWNING.

Application filed December 15, 1926. Serial No. 155,073.

This invention relates to new and useful improvements in storm shutters.

One object of the invention is to provide a storm shutter which, in general use, serves 5 the function of an awning.

Another object is to provide a device of this character which is adapted to be partially rolled up, when used as an awning, and to be unrolled, whereby to completely 10 close a window opening, for the purpose of protecting the window against breakage by high winds, and also to protect the window against fire.

Another object is to provide a device of 15 this character which is provided with a removable fabric cover, which gives the device the appearance of the ordinary awning.

Other objects and advantages will be apparent from the following description when 20 taken in connection with the accompanying drawing.

In the drawing:

Figure 1 is a front elevation of the device in the position of an awning, and partly 25 broken away.

Figure 2 is a vertical longitudinal central sectional view through the device, in the position of a protecting shutter.

Figure 3 is a transverse sectional view on 30 the line 3—3 of Figure 2.

Referring particularly to the accompanying drawing, 10 and 11 represent uprights which are L-shaped in cross section, as seen in Figure 3. Secured to and extending transversely between the upper ends of the uprights, is a cylindrical housing 12, and mounted within the housing is a transversely extending roller 13. The uprights 10 and 11 are provided with openings 14 for the passage of fastening devices (not shown), to secure the uprights to a window frame. Pivotally mounted in the outwardly extending flange portions of the uprights is an awning frame 15. Connected to the transverse portion of the frame 15 is the lower edge of a sheet of metal 16, and hinged to the upper edge of said metal sheet is the lower edge of a second similar sheet of metal 17. Hinged to each other, and having an end 45 one hinged to the upper edge of the sheet 17, are the transversely extending, but narrower sheets of metal 18. The sheet 18, at the other end of the series is movably connected to the roller 13. One end of the roller 50 13 is provided with a crank handle 19, by means of which the roller may be turned for

the purpose of rolling or unrolling the sheets 18. Secured to the sheets 16 and 17, by means of suitable separable fastening devices 20, is the awning fabric 21, which completely covers the metal plates, so that the device has the appearance of an ordinary awning.

When the device is to be used to completely close the window opening the operator 60 grasps the crank handle and rotates the roller 13 to unwind the narrower plates 18 so that the wider plates or sheets will move down toward the lower ends of the uprights, and lie within the angles of the uprights. 65 The awning frame 15 swings downwardly and inwardly, as the wider sheets move down. Thus the window opening is effectively closed, and protected against injury from external objects, driven by a high wind, 70 and also protected from the force of the wind. The fabric cover may be easily removed, when worn or faded, and replaced by a new one, such removal and renewal being readily accomplished by virtue of the separable fasteners.

When it is desired to restore the device to a position where it will again function as an awning, the operator grasps the lower or right portion of the frame 15, and pulls 80 same outwardly, away from the guides 10 and 11, and then rotates the roller, to wind the narrow plates on the latter. It is necessary to swing the lower portion of the frame 15 outwardly, so that said frame will not 90 bind against the guides, should an attempt be made to wind the plates 18 on the roller, without first moving the lower end of the frame outwardly beyond the vertical line of the pivotal connections of said frame with 95 the guides.

While I have described the shutter as being formed from metal, I wish it understood that the same may be formed from fire-proof material, such as asbestos, or the like. 100

The showing of the crank handle 19, for rotating the roller, is merely as a simple example of means for accomplishing such motion of the roller, and may be varied, as desired, without departing from the spirit 105 of the invention, or the scope of the appended claim.

What is claimed is:

A combined awning and shutter comprising a channeled frame adapted to be secured 110 to a window frame, an angular roller support in transverse position at one end of the

frame, a metal curtain including narrow plates movably connected together and adapted to be engaged with the faces of the roller upon rotation of the latter, wider plates connected together and to the narrow plates and arranged to extend downwardly and outwardly from the channeled members of the frame to form an awning when said narrow plates are wound on said roller, and
10 a pivotally mounted yoke carried by the

channeled side members of the frame and connected with the outer end of the outermost of the wider plates, all of said plates being adapted to lie within the channels of the frame to form a protective shutter for a 15 window when the narrow plates are wound from the roller.

In testimony whereof, I affix my signature.

RAYMOND L. MEYERS.
